ELECTROLYTIC CELL.

1,349,597.

Specification of Letters Patent. Patented Aug. 17, 1920.

Application filed April 2, 1919. Serial No. 286,950.

To all whom it may concern:

Be it known that we, HERBERT I. ALLEN and KENT R. Fox, citizens of the United States, residing at Portland, in the county 5 of Cumberland and State of Maine, have invented new and useful Improvements in Electrolytic Cells, of which the following is a specification.

This invention has for its object to provide an electrolytic cell of simple construction, in which the cathode and anode are so constructed and arranged as to afford a maximum conducting surface for the passage of the current through the electrolyte, 10 and in which certain other advantages will be obtained as hereinafter made plain.

In the embodiment of the invention selected for illustration and description, the tank is oblong in plan view. Resting thereon is the free-board section in which the chlorin is collected, and in which there may be a column of the electrolyte to increase the hydrostatic head. To the under side of the free-board section is attached the cathode 20 which is in the shape of a rectangular box or basket approximating the shape of but smaller than the tank, and which is suspended from the free-board section into the tank. By removing the free-board section, 25 the cathode and the anode may be removed bodily therewith from the tank. The box-like cathode is made of sheet iron and its sides, ends and bottoms are provided with numerous perforations for the passage of 30 the solution of brine and caustic and of the hydrogen. Within the cathode is an anode 35 with side, end and bottom faces confronting the corresponding parts of the cathode and closely adjacent thereto. Thus not only are 40 the side faces of the anode active, but also the end and bottom faces.

Referring now to the accompanying drawing,—

Figure 1 represents, in vertical longitudinal section, an electrolytic cell embodying 45 our invention.

Fig. 2 represents a plan view thereof.

Fig. 3 represents a horizontal section through the cell.

Fig. 4 represents a transverse vertical section through the cell.

Fig. 5 shows the cathode detached.

Fig. 6 shows a section on a larger scale, through one of the bolts by which the cathode is attached to the upper free-board sec-

tion of the cell, and shows how the cathode and the margin of the diaphragm are clamped thereto to make a water-tight and gas-tight joint.

Fig. 7 is a section of the cathode on a 60 large scale, showing how the diaphragm is arranged to cover the side and bottom walls thereof.

The cell, as shown, comprises the tank which is preferably made of iron or steel 65 sheets or plates, and which as stated is oblong in plan view. It has the bottom 10 with an upturned marginal flange 11 to which are riveted the plates or sheets (one or more) which are bent to constitute the 70 ends 12 and sides 13. From the bottom of the body leads a pipe 14 for conducting away the products of the electrolytic decomposition of the electrolyte.

The free-board section of the cell is pref- 75 erably made of slabs of slate, cast concrete or other inert material, of the proper dimensions, which are secured together in any convenient way to constitute the end walls 15 and side walls 16, flush with the correspond- 80 ing walls 12 and 13 of the tank. The upper end of the free-board section is closed by a cover consisting of a slab or plate 17 of similar material inert to chlorin. This cover is provided with holes to receive the feeding 85 tube 18, and the nipple 19 with which the conduit 20 is connected for conducting away the chlorin.

The cathode 21, as has been described, 90 consists of a sheet metal box or basket (preferably iron) having a bottom 22, sides 23 and ends 24, and it is of such dimensions as to fit within the tank and be spaced from the walls and bottom thereof, as shown in Fig. 4. All of the walls of the cathode are 95 provided with numerous closely spaced perforations,—preferably small slots in herringbone formation. At their upper edges, the end and side walls of the cathode are provided with out-turned marginal flanges 25. The 100 reentrant angles 26 at the corners of the box are filled with square plates 27, whose upper surfaces are located above those of the flanges a distance about equal to the thickness of the diaphragm when the latter 105 is under compression. The purpose of the flange will be subsequently explained; and it will suffice here to state that it is prefer- 110 ably in width substantially equal to the widths of the side and end walls of the free-

board section of the cell. The cathode tapers downwardly as indicated in Figs. 1 and 4.

Within the cathode is arranged a diaphragm to cover the side, end and bottom walls thereof. Preferably the diaphragm consists of one or more layers or strips of porous asbestos paper 28 laid lengthwise on the bottom of the cathode, and then bent upwardly so as to cover the end walls thereof as shown in Fig. 1, with its extremities bent outwardly to overlap the end flanges. The inner faces of the side walls of the cathode are likewise covered by sheets 29 of asbestos which terminate at and cover the bottom of the cathode (so as to furnish a double layer thereon) and which have their upper extremities overlapping on the side flanges 25. The reentrant angles, formed by the sheets 20 at the corners, are filled by the plates or blocks 27. A rectangular frame 30 of iron (either a casting or four bars suitably connected) is employed to clamp the flange of the cathode and the diaphragm to the under 25 side of the free-board section of the cell. Bolts 31 are passed through apertures in cover and in the sides and ends of the free-board section and are secured into the rectangular frame, and on the ends which project upon the cover are nuts 32, by tightening which the frame, the cathode, the margins of the diaphragm, the free-board section and the cover may all be clamped rigidly together. The frame merely rests upon 35 the upper edges of the walls of the tank, so that it and the parts connected thereto may be removed as a unit from said tank. The flanges 25 are imperforate, and the margins of the diaphragm between them and the 40 walls 15, 16, serve as packing and make a gas and liquid-tight joint to prevent the escape of liquor or gas. If desired, the margins may be impregnated with an insulating material inert to chlorin. Within the 45 cathode and the diaphragm there is located the anode which consists of the elongated carbon or Acheson graphite plates 33, which are shown as eight in number, with a set of four plates closely confronting each side 50 wall of the cathode and spaced from the other set. These plates are secured by carbon or graphite pins 34 to the upright carbon bars or rods 35 which space the sets apart and which project upwardly from 55 and through the cover 17. Said rods have connected to their exposed ends a bus bar 36 to which the positive lead wires of the circuit are connected. The anode may be hung from the cover, but preferably it rests upon 60 transverse supports 37 of insulating material such as glass, porcelain or other inert substance placed upon the bottom of the cathode. At the ends of the two sets of carbon plates or slabs 33, there are blocks or 65 bars 38 of carbon or graphite, which are

flush with the end faces of said plates or slabs 33, so as to form end faces or conducting surfaces confronting the surfaces or faces of the end walls of the cathode. The anode is thus in the shape, roughly, of an 70 oblong rectangular tube which is open at the top and bottom to permit the circulation of the electrolyte downwardly therethrough and upwardly through the spaces between the sides and ends of the anode and the cathode. 75 The bottom surfaces or faces of the anode confront the active bottom wall of the cathode, so that (except for the space between the two sets of anode plates) there is a maximum conducting surface, for the passage of the current through the electrolyte to the cathode. At one end of the cathode, the flange 25 is bent upwardly to provide a plate or extension 40 to lie outside of and parallel with the free-board section of the 80 cell as shown in Figs. 1 and 5. To this plate is secured a bus bar 41 with which the negative lead wire of the circuit is secured. 85

It will be understood, of course, that any suitable inert cement or other packing material is used to close any spaces between the walls of the apertures of the cover and the members which pass thereto, such as the feed well 18, the anode bars 35, and the gas nipple 19, to prevent the escape of 90 free chlorin into the atmosphere.

In practice, the sodium chlorid solution is fed continuously into the feed well (which has an eduction port or aperture 43 at its lower submerged end) from the usual float 100 valve, the level of the electrolyte being maintained preferably below the top of the cathode and above the tops of the anode plates. The electrolyte percolates through the porous diaphragm into contact with the 105 perforated side, end and bottom walls of the cathode. The caustic soda resulting from the reaction, together with the undecomposed brine, flows or drops into the bottom of the tank, and is continuously conducted 110 away therefrom through the discharge or eduction pipe 14 for concentration and evaporation of the caustic solution and removal of the salt therein contained. The chlorin liberated on the surfaces of the anode is collected in the free-board section of the cell and conducted away through the nipple 19 and the conduit 20.

The faces of the anode are close to the confronting faces of the cathode, the space 115 between them decreasing in width downwardly to compensate for the resistance of the anodes.

It is of course evident that, although we have described the cell as used for the electrolysis of an aqueous sodium chlorid solution, it may be employed for the electrolytic decomposition of other suitable chemical compounds.

From the foregoing description which we 120

- have given of the cell, it will be apparent to those who are skilled in the art that there are certain advantages resulting therefrom. It may be noted, for instance, that
- 5 practically the entire inner face of the cathode, including the bottom, sides and end walls, is electrically active, and that the exterior faces of the cathode are wholly un-submerged in any body of electrolyte, the
- 10 eduction pipe serving to insure the removal from the tank of the effluent from the cell. The flanges of the cathode are solid and not perforated, but the perforations in the side and end walls terminate at the corners
- 15 formed by the flanges and said walls, so that every part of the cathode which is in contact with the electrolyte is perforated so as to permit the free flow of the electrolyte and the emission of the hydrogen which
- 20 is liberated at the inner faces of the cathode outside of the diaphragm. By providing a water-tight and gas-tight pressure joint between the cathode and the free-board section, it is possible to build up the column
- 25 of electrolyte in said free-board section so as to secure the desired hydrostatic head as the diaphragm becomes more or less clogged with the impurities in the line, thus insuring a longer diaphragm life than would
- 30 otherwise be possible. The hydrogen, which collects in the tank, escapes through whatever crevices there may be between the top edges of the walls thereof and the rectangular frame which rests thereon, but, if de-
sired, of course, the tank may be provided
- 35 with a pipe outlet for conducting away and utilizing the hydrogen, in which case of course a suitable packing material may be interposed between the rectangular frame and the top of the tank.
- The bottom of the cathode is preferably provided with at least two layers of the asbestos sheets constituting the diaphragm so that the flow through the diaphragm and
- 45 cathode will be equalized by checking the flow through the bottom. The presence of the tank is of course desirable to prevent the admission of air to the hydrogen-containing space exterior of the cathode and
- 50 to prevent the formation of carbonates.
- Theoretically the best results are secured only when there are maximum surfaces of cathode and anode in proximity with the electrolyte between them so that all parts
- 55 of the cathode and anode are electrically active, for, where portions of the cathode or cell body are inactive, deterioration soon sets in and the efficiency of the cell is lowered. There is another consideration, how-
ever, to wit, that in order to prevent wast-
age of the current, there shall be a constant supply of saturated brine. In the cell, which we have herein described, it will be apparent that we not only provide for the
- 60 free flow of brine to the active surfaces of the anode and cathode, but that this is accomplished without diminishing to any ma-
terial extent the active surface of the cathode. To allow for the free passage of the electrolyte from one portion of the 70 anode chamber to another, the anode is, as previously stated, submerged slightly at least in the electrolyte, and at the bottom of the anode there is an open space through which the electrolyte may pass. If desired, 75 of course, the anode plates may be thicker so as to decrease the opening or passageway therethrough, and thus increase the active anode surface. We have found that the relative proportions, as illustrated in the draw- 80 ings, are desirable in that they provide for the presence of a relatively large body of electrolyte to prevent its too rapid impoverishment of salt, which of course would impair the efficiency of the cell.
- We should not regard it as a departure from the spirit and scope of the invention if the tank were filled with oil or other liquid immiscible with the caustic effluent, and by reference to the cathode being "ex- 90 teriorly unsubmerged" we have in mind a construction in which the exterior faces (side, bottom and the end walls) of the cathode are not in contact with an accumulation of the cell effluent.
- Having thus explained the nature of our said invention and described a way of making and using the same, although without attempting to set forth all of the forms in which it may be made or all of the modes 100 of its use, what we claim is:—
1. An electrolytic cell comprising a suitable tank, a rectangular box-shaped cathode having perforated active end, side and bottom walls, a diaphragm covering the inner faces of all of said walls, and a rectangular tubular anode of similar cross section disposed within the cathode, supported on the bottom thereof, and having end, side and bottom faces confronting and spaced from 105 the like active faces of the cathode.
2. An electrolytic cell comprising a suitable tank, a rectangular box-shaped cathode having active end, side and bottom walls all provided with perforations, a diaphragm 110 covering all the inner faces of the cathode walls, a rectangular tubular anode disposed within the cathode and having active faces confronting and spaced from the active side, bottom and end walls of the cathode.
3. An electrolytic cell comprising a rectangular tank, a removable rectangular free-board or top section resting thereon, a box-like cathode clamped to and suspended from said free-board section and having per- 115 forated side, end and bottom walls, a dia- phragm covering the inner faces of said walls and clamped between the cathode and said free-board section, and an anode ar- ranged within said cathode and having ac- 120 130

- tive side, end and bottom faces confronting and spaced from the inner faces of the corresponding walls of said cathode.
4. An electrolytic cell comprising a suitable tank with means for discharging the effluent therefrom to prevent the accumulation of the effluent, a tubular cathode and a tubular anode therein, said tubular cathode having active bottom and side walls which are externally unsubmerged and are spaced from said tank and also from said anode.
5. An electrolytic cell comprising a tubular open-end anode, the sheet metal tubular cathode inclosing and underlying the anode, and having its sides and bottom perforated and exteriorly unsubmerged, a diaphragm covering the inner faces of the sides and bottom of the cathode, and a tank in which said cathode is suspended with the sides and bottom spaced from the walls of said tank.
6. An electrolytic cell comprising a tubular open-end anode, a tubular cathode inclosing and underlying the anode, and having its sides and bottom perforated and exteriorly unsubmerged, a diaphragm covering the inner faces of the sides and bottom of the cathode, in combination with a tank, a free-board section resting thereon, and means for connecting the cathode and free-board section by a liquid-tight joint, whereby said cathode is suspended from the free-board section in the tank with the walls of the cathode spaced from the walls of the tank.
7. An electrolytic cell comprising a tank, a free-board section removably supported upon the upper edge of the tank, a cathode formed as a metal basket having perforated side, bottom and end walls, and having out-turned marginal flanges at its upper end, a porous diaphragm covering all the active faces of the cathode and having marginal edges out-turned over said marginal flanges, clamp bars secured to said free-board section to clamp the out-turned edges of the diaphragm and the out-turned flanges of the cathode to the free-board section to form a substantially gas-tight joint and enable the cathode to be suspended from the free-board section into the tank, and an anode within the cathode and having active faces confronting and spaced from the active faces thereof.
8. An electrolytic cell comprising a tank, a cathode formed as a metal basket suspended within said tank and having perforated bottom, side and end walls spaced from the walls of said tank, an anode occupying the interior of said cathode and supported on the bottom thereof, and insulating means interposed between said anode and the perforated metallic bottom wall of said basket.
9. An electrolytic cell comprising a cathode formed as a rectangular basket with perforated end, bottom and side walls, a diaphragm covering the inner faces of said walls, a free-board section from which said basket is suspended, a tank on the upper end of which said free-board section rests with the walls of the cathode spaced from the walls of the tank, and a tubular anode occupying the space in said cathode with active side, bottom and end faces confronting but spaced from the corresponding active walls of said cathode.
10. An electrolytic cell comprising a cathode formed as a rectangular basket with perforated end, bottom and side walls, a diaphragm covering the inner faces of said walls, a free-board section from which said basket is suspended, a tank on the upper end of which said free-board section rests with the walls of the cathode spaced from the walls of the tank, a tubular anode occupying the space in said cathode with its side, bottom and end faces confronting but spaced from the corresponding walls of said cathode, and insulators resting on the bottom wall of the cathode for supporting said anode.
11. In an electrolytic cell, in combination, a cathode formed as a rectangular metal basket with perforated end and side walls, a porous diaphragm covering the inner faces of said walls, and an anode occupying the space within the cathode and comprising spaced longitudinal side bars and end bars occupying the spaces between and secured to the ends of said longitudinal bars, all to form active faces confronting and spaced from the active faces of the perforated side and end walls of the cathode.
12. An electrolytic cell comprising a cathode consisting of a sheet-metal rectangular basket having perforated active side, end and bottom walls, a rectangular tubular anode having spaced longitudinal side bars and end bars between and secured to the ends of said side bars, all spaced from the end, bottom and side walls of the cathode, said side and end bars being below the top of the cathode, insulators resting on the bottom of the cathode for supporting the anode, and rods between and secured to said anode-side-bars for conducting the electric current thereto.
13. An electrolytic cell comprising a cathode consisting of a sheet-metal rectangular basket having perforated active side, end and bottom walls, a tubular anode having spaced longitudinal side bars and end bars between and secured to the ends of said side bars, all spaced from the end, bottom and side walls of the cathode, said side and end bars being below the top of the cathode, insulators resting on the bottom of the cathode for supporting the anode, rods between and secured to said anode-side-bars for conduct-

ing the electric current thereto, and an extension from one of the walls of said cathode for conducting the current therefrom.

14. In an electrolytic cell, in combination,
- 5 a cathode formed as a rectangular metal basket with perforated end and side walls, a porous diaphragm covering the inner faces of said walls, an anode occupying the space within the cathode and comprising spaced
  - 10 longitudinal side bars and end bars occupying the spaces between and secured to the ends of said longitudinal bars, all to form active faces confronting and spaced from the active faces of the perforated side and
  - 15 end walls of the cathode, a tank provided with draining means to prevent the accumulation of effluent therein, a free-board section adapted to rest upon the tank, and means for clamping said cathode to the un-
  - 20 der side of said free-board section to suspend it therefrom, with the bottom, side and end walls of the cathode spaced from the walls of said tank, whereby said cathode is exteriorly unsubmerged.
  - 25 15. An electrolytic cell comprising an up-

per closed free-board section, a metallic basket-like cathode attached to and suspended therefrom by a substantially liquid-tight joint and having perforated side, bottom and end walls furnishing active faces, a porous diaphragm covering the inner faces of the cathode, a tubular anode occupying the space within the cathode and spaced from the inner faces of the end, bottom and side walls thereof with its upper edges free to 30 permit the electrolyte to flow thereover, a tank on which the free-board section rests with the cathode suspended therein and spaced from the walls thereof, and means for withdrawing the effluent from said tank 35 to prevent the submergence of the cathode therein, said parts being so arranged that the level of the electrolyte in the free-board section may be above the top of the tank to increase the hydrostatic pressure. 40

In testimony whereof we have affixed our signatures.
